UNITED STATES PATENT OFFICE.

EDGAR E. GREVE, OF BELLEVUE, PENNSYLVANIA.

AUTOMATIC RELEASEING TONGS.

Application filed March 1, 1922. Serial No. 540,169.

This invention is for a pipe tong, and relates particularly to an automatic releasing tong especially adapted for use with rotary well drilling machines, or similar machines 5 wherein sections of pipe are threaded together by use of the machine.

In a rotary well drilling system, the tool or stem comprises a plurality of pipe sections connected by threaded tool joints which generally have a tapered box and pin connection and, in most cases, cooperating shoulders. The stem is rotated by means of a rotary or other suitable mechanism, and, as the depth of the well increases, new sections are added 10 to the stem. This is accomplished in most drilling mechanisms by holding the stem stationary in a temporarily fixed section of the rotary, while the section being added is screwed into the fixed stem by means of a pipe 15 tong which is rotated by a revolving table or ring of the rotary.

The rotary is of necessity a heavy machine, and the rotating part may attain considerable momentum. In many cases, therefore, when 20 pipe sections are being added, the revolving part of the rotary, and consequently the tong, is moving when the joint becomes tight or is "made up". As a result of this, some injury is apt to be done to some part of the drilling 25 rig.

The present invention has for its object to provide a tong which will release its grip on the section of pipe which it engages at the proper time, or at the time the joint is properly made up.

The accompanying drawings illustrate my invention. In the drawings:

Fig. 1 is a plan view of a tong embodying the invention;

Fig. 2 is a somewhat similar view, but with a part of the tong in section, and showing the gripping means moved to a slightly different position; and

Fig. 3 is a view somewhat similar to Fig. 2 of one modification of the invention.

Referring to the construction shown in Figs. 1 and 2 of the drawings, 5 designates the tong handle having a nose or pipe engaging portion 6, and having a rectangular opening 7 therein. In the nose are provided bits 8 or other suitable pipe engaging means. In some instances, rollers might be substituted for the bits.

The main jaw of the tong is designated 55 generally as 10, and has a curved pipe engaging portion 11 and a bifurcated handle

receiving portion 12, which forms two spaced apart ears. The pipe engaging portion 11 is preferably provided with bits 13.

In the rectangular opening 7 is a slidable 60 block 15 having a reduced extension 16. A shoulder is formed at 17. The interior of the block is drilled or hollowed out, a hole 18 being formed therein. Both ends of the block are open, but the opening toward the 65 pipe engaging end of the handle is restricted by flange 19.

A longitudinally extending bolt 20 is passed through the hollow interior of the block, its head being retained therein, while 70 its stem or shank projects out against the innermost end of the rectangular opening. Threaded on the bolt 20 is a nut 21 which may be fixed in position on the bolt by a pin or set screw 22. Against the nut 21 is a washer 23 75 which forms an abutment for one end of a still compression spring 24. The other end of the spring abuts against the shoulder 17. The bolt and block are thus relatively movable, that is, the bolt is slidable in the block, 80 but the inward movement is against the resistance of compression spring 24.

Passing transversely through block 15 and through the ears of the bifurcated end of the main jaw at a suitable position, is a pin or bolt 25 having a nut on one end thereof, or an equivalent means, for providing a pivot for the jaw and handle.

In the drawings, P designates the pipe. In Fig. 1, the tong is in pipe gripping position. Spring 24 urges the jaws into a tight gripping relation with the pipe. When the pipe joint is made up, the pipe resists further rotative movement, but the handle 5 continues to be moved. Consequently, the handle is forced outwardly, sliding bolt 22 inwardly to the position shown in Fig. 2, against the compression of spring 24. As the handle then continues to move, the jaw or nose 6 will be forced out of gripping engagement with the pipe and assume the position shown in dotted lines in Fig. 1, and the block and bolt will assume their normal position.

The arrangement shown in Fig. 3 is somewhat similar, but instead of the handle and the main jaw being movable relatively to each other, longitudinally, they are fixed against longitudinal movement and the handle is provided with a relatively movable nose. In Fig. 3, 30 designates the handle and 105 31 the main jaw. The jaw 31 is similar to that shown in Figs. 1 and 2. The pivot for 110

the jaw and handle is indicated at 33. In the lower end of the handle is a recess 34. A detachable jaw member 35 is provided, which has an extension 36 thereon extending into recess 34. In the recess 34 is a compression spring 37. A projecting rod 38 on extension 36 serves to slidably retain the jaw 35 in position.

10 The way in which the tong is shown in this modification is substantially the same as that described in connection with Fig. 1. When the pipe resists further rotative movement, resistance of spring 37 is overcome and the jaws are spread until jaw 35 has moved past 15 dead center, when it will be thrown out of gripping position. This modification is shown and claimed in my application Serial No. 34,847, filed June 4, 1925.

20 Various other changes and modifications may be made within the contemplation of the invention and within the scope of the appended claims.

What I claim is:

25 1. A pipe tong having a pair of pivotally connected pipe engaging members, one of which is movable arcuately with respect to the other and toward and away from the other, a spring for urging said movable member toward the other and resiliently holding 30 it in pipe engaging position, said movable member being moved in an arc and away from the other member to releasing position when the resistance of the pipe being turned by said tong exceeds the turning pressure applied to the tong and the resistance of the 35 spring.

2. A pipe tong having a pair of pipe engaging members, one of which has a handle extension which is out of alignment with the 40 pipe engaging portion thereof, a pivoting and slidable connection between the two members, and means for resiliently urging one of the members toward the other and effecting an automatic release of the tong from the pipe when a predetermined resistance is encountered, said means being operable while the tong is rotated in a single direction.

3. In a pipe tong, a jaw, a handle pivotally secured to the jaw and having pipe engaging 50 means, said handle and its engaging means movable in an arc and also away from the jaw to disengage the tong, and spring means for urging the handle and its pipe engaging means towards the pipe and permitting an 55 automatic release of the tong upon compression of the spring when a predetermined resistance is encountered, said means being operable to effect the said result while the tong is rotated in a single direction.

60 4. An automatic releasing tong including a pair of cooperating members one of which is movable in an arc relatively to the other into and out of pipe engaging position, one of said members being reciprocable toward 65 and away from the other, and means for re-

silently urging said reciprocable member toward the other and into pipe engaging position and effecting a release of the tong from the pipe while the tong is rotated in a single direction.

70

5. A tong comprising a handle having an opening therein near one end thereof and a gripping means at the end of the handle nearest the opening, a block in said opening, a bolt slidably engaging the block, there being 75 an abutment on the bolt and an abutment on the block, a compression spring interposed between the abutments, and a jaw pivotally connected with the block.

6. A tong comprising a handle having an 80 opening therein near one end thereof and a gripping means at the end of the handle nearest the opening, a block in said opening, a bolt slidably engaging the block, there being 85 an abutment on the bolt and an abutment on the block, a compression spring interposed between the abutments, a jaw having a bifurcated extension thereon adapted to receive the handle, and a pin passing through the bifurcated extension and through said 90 block for pivotally connecting the jaw and handle.

7. A pipe tong comprising a handle on which is carried an operating jaw, a main jaw pivotally and slidably connected with the handle, whereby the operating jaw may be swung in an arc relatively to the main jaw and may slide incidental to swinging when resistance to turning beyond a predetermined degree is offered by the pipe, and means whereby the 100 radius of the arc through which the operating jaw travels may be varied for each point of contact with an object being gripped.

8. A pipe tong comprising a handle having a gripping jaw thereon, and an opposed jaw, 105 said gripping jaw carried at the end of the handle and out of alignment therewith, means pivotally and slidably connecting the other jaw and the handle, means for normally holding the jaws in a gripping position, said second mentioned means enabling the jaws to spread when an object being turned thereby offers resistance to further movement beyond a predetermined amount.

9. In a pipe tong, a jaw member, a handle 115 pivotally secured to the jaw member and having pipe engaging means, means for urging the said pipe engaging means into operative engagement with a pipe and effecting an automatic release of the tong from the pipe 120 when a predetermined resistance is encountered, said means being operable while the tong is rotated in a single direction.

10. In a pipe tong, a jaw member, a handle 125 member pivotally secured to the jaw member, a spring-projected pipe-engaging means on one of the members, and a pipe-engaging means on the other member, said handle member being movable in an arc from pipe-engaging to pipe-releasing position upon forcing 130

the spring-projected pipe-engaging means to retracted position.

11. A self-releasing tong comprising a jaw member, a handle member pivotally carried at one end of the jaw member, a spring-projected pipe-engaging element on one of the members, and a pipe-engaging element on the

other member, said handle member being movable in an arc from pipe-engaging to pipe-releasing position upon forcing the 10 spring-projected pipe-engaging element to retracted position.

In testimony whereof I affix my signature.
EDGAR E. GREVE.
